COMBINED WINDOW HANDLE AND LATCH THEREFOR

Thomas D. Terrian, 9871 Doris, Livonia, Mich.

Filed May 12, 1964, Ser. No. 79,945

Term of patent 3½ years

(Cl. D10—8)

The dominant features of the design reside in the portion shown in solid lines.

I claim:

The ornamental design for a combined window handle and latch therefor, as shown and described.
